UNITED STATES PATENT OFFICE.

WILLIAM A. HEATHCOCK, OF LOWELL, MASSACHUSETTS.

MACHINE FOR MAKING CORE-YARNS.

1,286,311.

Specification of Letters Patent.

Patented Dec. 3, 1918.

Application filed May 26, 1916. Serial No. 100,119.

To all whom it may concern:

Be it known that I, WILLIAM A. HEATHCOCK, a citizen of the United States, residing at Lowell, in the county of Middlesex and 5 State of Massachusetts, have invented certain new and useful Improvements in Machines for Making Core-Yarns, of which the following is a specification.

This invention relates to what are known 10 as core yarns. It has especial reference to the process of forming core yarns and to a machine for carrying out my process of making such yarns.

A core yarn comprises a core which usually 15 consists of a spun or twisted, substantially finished yarn of smaller size than the complete core yarn, and a relatively thick cover or exterior which more or less envelops the core. Where the cover is relatively thin, 20 it is sometimes called a covered yarn.

The exterior has been made of undrawn, 25 untwisted fiber such as the film from a card, it has been made of sliver, of spun or twisted yarn, and of a ribbon of filaments, such as 50 of silk or artificial silk.

The exterior may be twined or wound around the core in which case it will be of 30 greater length than the core. They may be twisted together in which case they are wound or spiraled one around the other with 35 the result that while with a heavy exterior, the core, to a great degree, sinks in out of sight, it shows in spots and of course is not 40 in the axial center of the finished yarn.

To clearly understand my invention, it is 45 necessary to have clearly in mind the meaning of the terms used, and I therefore now state that the lap or sheet of fiber which is fed to a card, emerges as a film. This film, 50 as on a woolen card, may be divided into roping or sliver; or it may, without being divided, be condensed into a sliver. In either case, the sliver has no twist, its fibers are not 55 parallel, and it is uneven.

This sliver is doubled and drawn and 60 finally given a slight twist by suitable machinery when it becomes slubbing and roving. Roving is more even and its fibers are 65 more parallel than is the case with a film, or sliver.

Such roving may be twisted into yarn 70 without further drawing, or it may be spun on suitable spinning machinery whereby it is drawn out and then revolved about its 75 longitudinal axis to form spun yarn.

The principal purposes of my invention are to utilize well known machines without complicated attachments, and their products, to produce, by unskilled labor, as cheaply as possible, a stronger core yarn which is uniformly even, in which the core is at the axial center and is not spiraled, and in which the exterior and core are so spun together that each helps to strengthen the other. 60

With my invention, I can use unskilled labor, and economize floor space by using compact machines, such as ring spinning frames of high relative production. 65

Another purpose of my invention is to use as an exterior, a fiber which is so short 70 that as a sliver or roving, it will not support its own weight except when in very short lengths or of very large size. It is especially useful for short china cotton, but I may use a fiber of long staple such as cotton, wool, jute 75 or other similar material.

I have discovered that where the film or sliver from a card is rubbed onto a core, so as to surround it, and the product is wound onto a spool, the core will separate from its 80 covering in spots and will also cut into the inside coils so that it will not unwind.

I have also discovered that if the cover and core are run together any distance without 85 or before they are revolved, they will separate and the resulting yarn will be uneven, but that if the cover consists of roving which is flattened out by pressure devices, preferably rolls, and the core yarn is so guided as to engage it at a substantially laterally central position in the outside of the roving as 90 both pass through such devices, the core is forced into the cover and if both are at once revolved as they leave such devices, a spun core yarn of the character described is produced. 95

In such core yarn, the roving is wrapped or spun around the core, not twisted nor wound thereon, and the whole mass is so homogeneous, that it all breaks together instead of the core breaking first when put under a strain. 100

With my invention, I use roving which has been doubled and drawn to make it even and its fibers parallel. This is wound as 105 usual upon bobbins, which are revolubly mounted in a creel so as to be unwound by the pull of the roving as it passes through the drawing rolls. I prefer to pass this roving through a plurality of sets of drawing 110

rolls, the speed of which can be varied, whereby the amount of cover can be regulated.

The speed of these sets of rolls successively increases from the feed to the delivery rolls and each set preferably comprises a fluted metal bottom roll and a smooth leather covered top roll, which has some elasticity or give.

10 Spools upon which the yarn to form the core is wound are revolubly mounted in a creel so as to be unwound by the pull of the yarn as it passes through the set of delivery rolls.

15 I use a guide or guides, preferably of the traversing type, and of the special form shown, to so guide the yarn as to unite it with, preferably the center of, the roving as it enters between the delivery rolls, and as 20 a means for revolving the yarn and roving as they leave the delivery rolls, I use the well known ring and traveler of the ring spinning frame.

I can use my invention with a ring spinning frame as described, with a roving frame, intermediate, fly frame or a cotton mule, or with any spinning machine as distinguished from a twister, by employing suitable guiding devices.

25 30 In the drawings I show my invention applied to a well known form of ring spinning frame.

In the drawings Figure 1 is an elevation showing part of a ring spinning frame from 35 the side. Fig. 2 is a sectional side elevation showing the details of the drawing rolls and adjacent parts, together with one form of traversing guide. Fig. 3 is a back elevation of such guide. Fig. 4 is a side elevation of

40 another form of guide. Fig. 5 is a front view of part of a ring spinning frame showing the roving from the bobbins, yarn spools, and spindles. Fig. 6 is a front elevation of part of a ring spinning frame 45 showing the guide eyes, drawing rolls and spindles in the relation in which they are on some types of machines.

A represents a two storied creel upon the upper part of which are mounted the roving bobbins 10 in staggered relation in a well known manner, whereby each is revoluble by the pull of its roving as 11, which passes over a guide rail 12 thence down through traversing guide B, and through the drawing rolls 20, 21, 22, 23, 24, 25, as 50 will be described. In Figs. 1, 2 and 4 the roving from one spool only is shown for the sake of clearness.

I also mount on the lower part of creel A, 60 spools 30, 30 on each of which is wound, spun or twisted yarn 31, and each of which is so mounted as to be revoluble by the pull thereof. The yarn 31 may be guided by yarn guide rail 32, and thence passes 65 through one of the bottom eyes of guide B,

thence under the lower back and middle drawing rolls and up between the front drawing rolls as shown.

The drawing rolls are of the well known type, and may be set in the usual manner in 70 accordance with the amount of draft on the roving desired, and the thickness of the cover for the core yarn which is wanted. They are arranged in sets, of which 22—25 are the feed or back rolls; 21—24 the intermediate or middle rolls, and 20—23 the delivery or front rolls. These sets of rolls are of successively increasing speed, from the feed to the delivery rolls. The bottom rolls are preferably of metal and fluted, while the 80 top rolls are preferably covered with padding and leather.

The guides B of which, as shown, there is one for each two spindles, are carried by the traverse bar 34, which moves back and forth from side to side of the frame behind the drawing rolls in a well known manner, and by well known mechanism. Each is shown as having at the top, trumpet guide eyes 35 and 36, each of a size to allow the 90 passage of the undrawn roving, and at the bottom, each directly underneath, a top guide eye, the bottom trumpet guide eyes 37 and 38, each of a size to permit the passage of the core yarn from a spool 30. 95

The roving 11 passes directly through all the sets of drawing rolls and is drawn out to the extent desired, while directly underneath it and so guided by an eye, such as 37 or 38, the core yarn 31 passes below the bottom, back and middle rolls and joins the flattened out roving, preferably directly at the center thereof, as it enters between the front or delivery rolls.

As soon as it emerges, it is revolved by the action of its spindle 40 and bobbin 41, and is spun and laid upon the bobbin in the usual manner by the action of the ring 43 and traveler 44. In Fig. 5 the guide wires 46 are shown as directly in line with, or in the same plane with the middle point of the traverse of a guide and a spindle, and for the best results I prefer such an arrangement.

On some frames however, as shown in Fig. 6, on account of the length of the drawing rolls and their arrangement, the distance between adjoining guide eyes, such as 60 and 61, is less than that between spindles 62 and 63, and the guide wires 64 and 65. This has a tendency to pull the core yarn away from the cover and to counteract this I may use a guide such as shown in Fig. 4, which consists of a wire 71 having a loop 72 at the end of an arm 73 bent upwardly at one end and having another arm 74 bent upwardly at the other end and fastened directly underneath a roving guide eye 75, carried by traverse bar 34. With this type of guide, the core yarn may be guided almost directly into the roving as it enters the delivery rolls, and

there is less likelihood of its being pulled away by reason of the spindle being offset.

As the roving on spools 10 may be of any desired size, very short stock can be used, 5 and this can be drawn down by the drawing rolls to be very fine by regulating the speed, by using small sized intermediate and delivery rolls, and setting them closely together. The roving will thus hold together, 10 and its longer fibers will tend to move toward the center, so that as the core yarn is directly in the center and both are revolved at once as they leave the delivery rolls, a very strong even yarn is produced, having 15 the core at the center and next thereto the long fibers, while the short fibers are on the outside.

It is evident that it makes no difference which way the yarn is revolved.

20 I claim:

1. The combination of a bobbin on which roving is adapted to be wound revoluble by the pull of the roving, with a plurality of sets of drawing rolls of successively increasing speed comprising sets of feed and delivery rolls through which the roving is adapted to pass, with a spool on which spun or twisted 25 yarn is adapted to be wound revoluble by the pull thereof, a traversing guide located back 30 of the feed rolls with a top eye for the roving and a bottom eye directly under it for the yarn, to guide the yarn to unite it with the roving as it enters between the delivery rolls, and means for revolving the yarn and 35 roving as they leave the delivery rolls.

2. The combination of a bobbin on which roving is adapted to be wound revoluble by the pull of the roving, with a plurality of sets of drawing rolls of successively increasing 40 speed comprising sets of feed and delivery rolls through which the roving is adapted to pass, with a spool on which spun or twisted yarn is adapted to be wound revoluble by the pull thereof, a traversing guide with a top 45

eye for the roving and a bottom eye directly 45 under it for the yarn, to guide the yarn to unite it with the roving as it enters between the delivery rolls, and means for revolving the 50 yarn and roving as they leave the delivery rolls.

3. The combination of a bobbin on which roving is adapted to be wound revoluble by the pull of the roving, with a plurality of sets of drawing rolls of successively increasing speed comprising sets of feed and delivery 55 rolls through which the roving is adapted to pass, with a spool on which spun or twisted yarn is adapted to be wound revoluble by the pull thereof, a traversing guide located back of the feed rolls with a top 60 eye to guide the roving between the feed rolls and a bottom eye below and in line with it to guide the yarn under the feed rolls so as to unite it with the roving as it enters between the delivery rolls, one of which is a 65 cushioned roll, and means for revolving the yarn and roving as they leave the delivery rolls.

4. The combination in a spinning frame of one or more bobbins free to revolve on 70 which roving is adapted to be wound, and one or more spools free to revolve on which spun or twisted yarn is adapted to be wound, with a plurality of sets of drawing rolls of 75 successively increasing speed comprising sets of feed and delivery rolls through which the roving is adapted to pass, a traversing guide located behind the feed rolls having a top eye for the roving and a bottom eye directly under it for the yarn, to guide the 80 roving between the feed rolls and to guide the yarn under the feed rolls to unite it with the roving as it enters between the delivery rolls, and means for revolving the yarn and roving as they leave the delivery rolls. 85

In testimony whereof I hereto affix my signature.

WILLIAM A. HEATHCOCK.
